(57) **CLAIM**

We claim, the ornamental design for a measurement device, as shown and described.

DESCRIPTION

FIG. 1 is a front right perspective view of the invention; FIG. 2 is a rear right perspective view of the invention; FIG. 3 is a left side view of the invention; FIG. 4 is a right side view of the invention; FIG. 5 is a rear view of the invention; FIG. 6 is a front view of the invention; FIG. 7 is a top view of the invention; and, FIG. 8 is a bottom view of the invention.

The evenly spaced dashed lines and unshaded portioned contained within the broken lines shown in FIG. 1-FIG. 8 form no part of the claimed design.

The dash-dot lines shown in FIGS. 1-7 indicate the boundary of an arm portion and form no part of the claimed design. References to "side", "top", "front", "rear" and "bottom" in the figure descriptions are not meant to require certain in-use orientation; a measurement device according to the claimed design may be used in any orientation.
